UNITED STATES PATENT OFFICE.

JULIUS E. BIRO, OF FAIRCHANCE, PENNSYLVANIA.

FENDER.

1,103,392.

Specification of Letters Patent. Patented July 14, 1914.

Application filed March 3, 1914. Serial No. 822,204.

To all whom it may concern:

Be it known that I, JULIUS E. BIRO, a citizen of the United States, residing at Fairchance, in the county of Fayette, State 5 of Pennsylvania, have invented certain new and useful Improvements in Fenders, of which the following is a description, reference being had to the accompanying drawings, forming a part hereof.

10 My invention relates to fenders for vessels and has for its object to provide an inexpensive and effective device capable of being readily attached to and detached from a vessel which will push away smaller 15 masses of ice and will protect the vessel from injury from striking larger masses.

With these and other objects hereinafter set forth in view my invention consists in the construction and combination of parts 20 hereinafter described and particularly pointed out in the claims.

Referring to the drawings Figure 1 is a plan view of a fender embodying my invention shown in position on the bow of a vessel. Fig. 2 is a side elevation of the construction shown in Fig. 1. Fig. 3 is a front elevation of the fender which is carried by the cutwater. Fig. 4 is a horizontal sectional view on line *a*—*a* of Fig. 2 and Fig. 5 is a 30 vertical sectional view on line *b*—*b* of Fig. 1.

In the drawings 1 indicates the bow of a vessel of which 2 is the cutwater.

3 indicates a vertical bar preferably provided with a buffer face 4 made up of an upper portion 4' an intermediate portion 4² and a lower portion 4³. Between the portions 4' and 4² and between the portions 4² and 4³ the bar 3 is provided with horizontal bores 5 and 6 through 35 which extend rods 7 and 8 headed at their outer ends and each having its inner end screwthreaded into a block of suitable material 9 preferably nearly spherical in form and having a V-shaped recess 10 in its rear 40 which extend rods 7 and 8 headed at their outer ends and each having its inner end screwthreaded into a block of suitable material 9 preferably nearly spherical in form and having a V-shaped recess 10 in its rear 45 to fit a plate 11 which is bent to fit over the cutwater of the vessel. On each of the rods 7 and 8 is arranged a coiled spring 12 each bearing at its forward end against the bar 3 and at its rear end bearing against 50 one of the blocks 9, these springs acting to hold the bar 3 normally ahead of the cutwater a distance depending on the length of the rods 7 and 8.

In order to keep the bar 3 in proper position in line with the cutwater flexible connections here shown as chains 13 are pro-

vided each secured at one end to an eyebolt 14 carried by the bar 3 and at the other end to an eye bolt 15 carried by the plate 11. In order to hold the bar 3 from vertical movement flexible connections 16 and 17 here shown as chains extending respectively from an eye bolt 18 at the upper end of bar 3 to an eye bolt 19 secured to the cutwater above the level of the upper end of the bar 3, and from an eyebolt 20 at the lower end of bar 3 to an eyebolt 21 on the cutwater below the level of the lower end of the bar 3.

In order to attach the device as above described to a vessel it is necessary only to lower it over the cutwater with the plate 11 fitting over the cutwater as shown and secure the flexible connections 16 and 17 to their eyebolts.

The device as above described may be used 75 by itself and will protect the bow of the vessel effectively but I prefer to use also the fenders shown on the sides of the bow. These side fenders are similar in construction to the cutwater fenders already described except that the bar is arranged horizontally instead of vertically. The side fenders each comprise a bar 25 provided on its outer face with a buffer face 26 made up of end-portions 26', and 26² and intermediate portions 26³. Between the end portions and the intermediate portions the bar 25 is provided with bores 27 and 28 through which extend rods 29 and 30 having heads at their outer ends and having their inner 80 ends secured in plates 31 and 32 which are adapted to be secured to the sides of the vessel in any convenient manner and each carrying a coiled spring 40 bearing at its outer end against the bar 25 and at its inner end against plate 31 or 32. The bars 25 are supported in position by flexible connections 33 each secured at its outer end to an eyebolt 35 near the forward end of the bar and secured at its inner end to an eye- 85 bolt 36 on the side of the vessel, and by flexible connections 34 each secured at its outer end to an eyebolt 37 near the rear end of the bar, and secured at its inner end to an eye bolt 38 on the side of the vessel. 100 These side fenders will normally be held in the position in which they are shown that is with the bars 25 held away from the side of the vessel by the springs 40. If the vessel comes in contact with a considerable mass 105 of ice the portions of it which pass on either side of the cutwater and which would be

apt to damage the side of the vessel will strike one or the other of these side fenders and be held away from the vessel the springs 40 yielding to any severe impact preventing any serious shock.

5 The bars 3 and 25 are preferably formed of wooden beams of suitable size depending somewhat on the size of the vessel on which the device is to be used. The buffer faces 4. 10 and 26 are also preferably formed of wooden beams and the several portions of these buffer bars are preferably secured to the bars 3 and 25 by screws as shown so as to be removable to be replaced by others when 15 worn by use.

Having thus described my invention what I claim is,

20 1. In a detachable fender for vessels, the combination with a bar having openings therein, rods extending through the openings having their outer ends headed and having their inner ends arranged to have a bearing against a portion of the vessel and each provided with a spring between the bar 25 and the vessel, detachable flexible connections between the bar and the vessel and flexible connections between the bar and a portion of the fender.

25 2. In a fender for vessels, the combination with a bar having openings therein, rods extending through the openings, said rods having their outer ends headed and having their inner ends arranged to have a bearing against a portion of the vessel and each pro-

vided with a spring between the bar and the vessel, flexible connections between the bar and the vessel, and a buffer face detachably secured to the front of the buffer bar made up of portions spaced apart to permit the ends of the rods to move between the portions.

35

3. In a detachable fender for vessels, the combination with a bar having openings therein and arranged vertically in front of the cutwater of the vessel, a plate detachably fitting over the cutwater, rods carried by the plate arranged to extend through the openings in the bar, springs carried by the rods between the plate and the bar and flexible connections between the plate and the bar.

40

4. In a detachable fender for vessels, the combination with a bar having openings therein and arranged vertically in front of the cutwater of the vessel, a plate slidably mounted over the cutwater, rods carried by the plate arranged to extend through the openings in the bar, springs carried by the rods between the plate and the bar and flexible connections between the plate and the bar and flexible connections between the bar and the vessel.

45

This specification signed and witnessed this 28th day of Feb., A. D. 1914.

JULIUS E. BIRO.
